(57) **CLAIM**

The ornamental design for a joint nut for attaching fluid pump to container as shown and described.

DESCRIPTION

FIG. 1 is a perspective view of a joint nut for attaching fluid pump to container showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is cross-sectional view taken along line A-A' of FIG. 6.

FIG. 8 is a bottom plan view thereof; and,

FIG. 9 is a bottom perspective view thereof.
